D. T. DAY.

APPARATUS FOR TREATING HYDROCARBON OILS.

APPLICATION FILED DEO. 7, 1910.

1,004,632.

Patented Oct. 3, 1911.

UNITED STATES PATENT OFFICE.

DAVID T. DAY, OF WASHINGTON, DISTRICT OF COLUMBIA.

APPARATUS FOR TREATING HYDROCARBON OILS.

1,004,632.

Specification of Letters Patent.

Patented Oct. 3, 1911.

Application filed December 7, 1910. Serial No. 596,017.

To all whom it may concern:

Be it known that I, DAVID T. DAY, a citizen of the United States, residing at Washington, in the District of Columbia, have invented certain new and useful Improvements in Apparatus for Treating Hydrocarbon Oils, of which the following is a specification.

This invention relates to apparatus for treating crude petroleum or its distillate products which are bad in odor and deficient in hydrogen, for increasing the yield and improving the quality of light hydrocarbon oils, lubricating oils and other products of distillation; also for improving the quality of the resulting residuum; and is an improvement on the invention secured to me by Letters Patent No. 826,089, dated July 17, 1905.

It has heretofore been found that the contact or catalytic action of porous bodies, such as spongy metals or porous clays, enable petroleum vapors or liquids, under appropriate temperature and pressure, to combine with hydrogen, with the production of superior products, due to the added hydrogen. Thus it was ascertained that when gases or vapors carrying hydrogen, such as water gas, or ethylene and its homologues were brought in intimate contact with petroleum vapors or liquids in the presence of a porous medium capable of exerting the action usually described as contact action, or catalytic action, the hydrogen was added to, or combined with, the previously unsaturated hydrocarbons, with the desirable effect of producing hydrocarbons containing more hydrogen than before, in proportion to the amount of carbon. As a result, the distillates and residuum are lighter in color and sweeter in odor, the kerosene being more suitable for burning in lamps, the gasoline better for illuminating and power purposes and the heavy oils much improved for lubricating purposes. It has especially been found that when such crude petroleums or residues are subjected to the cracking process to increase the yield of light oils suitable for burning in lamps and of gasoline, the addition of hydrogen, through the medium of a contact agent, is rendered especially easy and efficient, and the yield and quality of the valuable products is thereby greatly increased.

The principal object of my invention therefore, is to provide an apparatus adapt-

ed for carrying out the process of deodorizing hydrocarbon oils and increasing the yield of light oil, by mingling or combining with the oils under treatment a sufficient percentage of hydrogen to convert them into a mixture of the marsh-gas series of hydrocarbons and other series richer in hydrogen than the cracked products.

A special object of my invention is to provide for effectively and economically superheating commingled streams of oil vapor and hydrogen carrying gas in a hydrogenator, by passage through the porous absorptive contact material in tubes immersed in the liquid which is being distilled, thereby aiding and expediting the process of combining hydrogen with the oil vapor for the purpose of saturating the oil and improving its quality. In this superheating operation I also provide for regulating and controlling the temperature to that degree, which is most effective for carrying out the contact process, by controlling the pressure and consequently the temperature of distillation, directly in the still.

Another object is to provide an improved construction of apparatus by means of which the process can be more economically and effectively carried out. By my improved construction the first cost of constructing the apparatus is reduced, and the subsequent expense of operating it to carry out the process is much reduced.

I will now more particularly describe my invention by reference to the accompanying drawings in which—

Figure 1 represents a vertical longitudinal section of an oil still with parts in elevation, embodying my improvements and adapted for carrying out my process, Fig. 2 represents a vertical transverse section line 2—2, Fig. 1.

In my apparatus the hydrogenator is constructed in, and as a part of, the oil still, the construction being as follows: An oil still A is set in a suitable furnace and its opposite ends are provided respectively with manholes and covers a, a' to give access for cleaning and repairing. Near the opposite ends of the still are secured transverse partition plates B, B¹, forming vapor spaces b and b¹, and a space between them for the body of oil to be distilled. The plate B does not extend to the top of the still, or is provided with a top opening c for the passage of oil vapor and hydrogen into the vapor

space *b*; it is also provided near the bottom with a manhole and cover *b'*. The plates *B*, *B'*, may be termed tube-sheets and are connected by tubes *d* for containing the porous absorptive material *e*. These tubes connecting with the plates *B*, *B'*, constitute the hydrogenator *D*, the tubes being immersed in the body of oil which usually rises to the level indicated by dotted lines *a*. A 5 perforated pipe *F*, having a valve *f*, extends longitudinally near the bottom of the still for admitting oil and hydrogen or either one alone, as required. With the outer end of pipe *F* connects an oil supply pipe *F'*, having a valve *f'*; also a hydrogen supply pipe *G* having a valve *g*. I preferably construct 10 a hydrogen generator *H* near the still, so as to be able to supply hot hydrogen through pipes *G* and *F*. This generator may consist of retorts in which oil is decomposed for 15 liberating hydrogen, or may be any other desired form of hydrogen generator. The goose neck or vapor escape pipe *J*, having a controlling valve *j*, connects with the vapor chamber *b'* and with any well known form 20 of condenser *K*. A pressure gage *m* is connected with chamber *b'* for indicating the pressure in the still, as a guide for properly adjusting the valve *j*. The contact material, 25 in the nature of a porous absorptive substance *e*, such as a finely divided metal or finely divided clay, is placed in the tubes *d* to nearly fill the same.

The operation may be conducted as follows:—Oil is supplied to the still, filling the same to the dotted line *a* and when suitably heated for the purpose of distillation, hydrogen or a hydrogen carrying gas or vapor is forced in through the perforated 30 pipe *F* and passed up through the body of oil. The commingled hydrogen and oil vapors, rising into the vapor space at the top of the still, pass therefrom through opening *c* into the chamber *b* and thence 35 through tubes *d* in contact with the porous absorptive material *e* therein, where the catalytic action takes place, resulting in the hydrogen being combined with the previously unsaturated hydrocarbons and producing 40 hydrocarbons containing more hydrogen than before in proportion to the amount of carbon. The hydrogenating tubes being immersed in the body of oil which is being distilled are heated by the 45 oil to a temperature as high as the distillation temperature of the oil, and for practical purposes they will be heated to a higher degree than the vapor, inasmuch as liquid from which oils are being distilled is always 50 hotter than the distillate vapors passed off from it. By this means the commingled hydrogen and oil vapor are superheated, thereby causing the hydrogen to combine with the oil vapor in the presence of the contact 55 material and produce saturated oil contain-

ing an increased percentage of hydrogen. I thus utilize the heat of the comparatively highly heated body of oil for superheating the commingled hydrogen and oil vapor and effecting saturation of oil with hydrogen. 70 The saturated vapor now passes off into the outlet chamber *b'* and thence through the goose neck *J* to the condenser *K*.

In order to regulate the temperature and maintain it at that degree most suitable to the contact process involved, the valve *j* will be adjusted and may be so set as to increase the pressure, and, consequently, the temperature of the body of oil in the still. The temperature of distillation can thus be controlled. If the temperature of the body of oil is raised the hydrogen and oil vapors will be more highly superheated during passage through the tubes *d*. This is quite important in practice, in order to control 80 the operation of combining hydrogen with oil vapor for saturating the same. An attendant, by observing the pressure indicated in the gage *m* will understand how to adjust the valve *j* for producing the desired pressure and temperature in the still. Hot hydrogen is preferably passed from the generator *H* directly through the perforated pipe *F*, thereby materially aiding the heating of the oil. A stream of oil and heated 85 hydrogen may be admitted simultaneously through pipes *F'* and *G* into pipe *F* and discharged therefrom into the still. Should it be desired to increase the pressure and temperature of the commingled hydrogen and 90 oil vapor in contact with the process material *e* in the tubes *d* for expediting or increasing the catalytic action or hydrogenating operation, the valve *j* may be partially closed and so adjusted as to secure the desired effect. 95

As contact agents for causing hydrogen to combine with petroleum oils, I may use finely divided metals, or metals in the porous condition, such as iron by hydrogen, zinc 100 dust, reduced nickel or cobalt, dry porous clays, spongy platinum, or palladium, coating clays, or quartz, in fact any agent capable of bringing hydrogen into intimate contact with the petroleum compound. 110 Whether the contact agent in some cases, as palladium, first forms a compound or alloy with the hydrogen, is immaterial to the final effect, which is that of yielding oil of better quality as the result of the contact action. 115

As an illustration of the practical operation of this process the tubes *d* of a still of 100 barrels capacity are first charged with briquets of copper or iron oxid mixed with metallic dust, the choice of the contact agent 120 depending upon the market price of an available supply. The still is charged with Mexican crude oil of 16° B. gravity; the still is then heated until the first condensed vapor from the minute amount of gasoline 125 130

present in the crude oil, appears from the condenser, at the ordinary pressure of the atmosphere. Then hydrogen, preferably as hot as possible, from the generator is passed 5 in through pipe F at a rate that may well be averaged at 6 cubic feet per second. Inasmuch as this hydrogen is little purer than producer-gas and not of much value an excess is provided. The excess issuing with the 10 vapors which at once begin to appear from the condenser, is usually fed to the fire under the still. In the case of oils of as high boiling points, as that of 16° B. gravity no extra pressure is used, unless the use of excessive 15 hydrogen is undesirable. In that case the hydrogen will yield lighter products if the extra pressure goes to 50 pounds per square inch. In the case of lighter oils from California, Texas or other localities, 20 extra pressure is employed to retard boiling of the oil until a suitable cracking temperature is reached, say 250° C. to 350° C. With the progress of the distillation crude oil is introduced in the manner above described 25 in order to maintain the level of the oil as nearly as may be until impurities collect and require interruption of the process for cleaning out the still.

Having described my invention, what 30 I claim, and desire to secure by Letters Patent, is—

1. The combination with an oil still, of a hydrogenator therein, comprising two vapor chambers, an intermediate oil chamber, tubes 35 connecting the vapor chambers, the partition between the oil chamber and one vapor chamber having an opening for the passage of vapors to the tubes, and a goose neck or vapor escape pipe connecting with the other 40 vapor chamber, substantially as described.

2. The combination with an oil still, of a hydrogenator therein, comprising two vapor chambers, an intermediate oil chamber, tubes connecting the vapor chambers, the partition 45 between the oil chamber and one vapor chamber having an opening for the passage

of vapors to the tubes, a vapor escape pipe connecting with the other vapor chamber, and a pipe leading from a source of supply of hydrogen-carrying gas or vapor and connecting with said oil chamber, substantially as described. 50

3. The combination with an oil still, of a hydrogenator therein, comprising two vapor chambers, an intermediate oil chamber, 55 tubes containing porous absorptive contact material connecting the vapor chambers, one of the dividing partition plates having an opening for the passage of vapors from the oil chamber into the first vapor chamber, a hydrogen supply pipe connecting with the oil chamber and a vapor escape pipe connecting with the second vapor chamber, substantially as described. 60

4. The combination with an oil still having the vapor chambers, an intermediate oil chamber connecting directly with one of the vapor chambers, and tubes connecting the vapor chambers through the oil chamber, of a generator for hydrogen carrying gas or 70 vapor, a pipe connecting the same with the oil chamber for supplying hot gas or vapor thereto, substantially as described. 65

5. The combination with an oil still, of a hydrogenator therein, comprising two vapor 75 chambers, an intermediate oil chamber connecting directly with one of the vapor chambers, tubes connecting the vapor chambers, and containing porous contact material, a hydrogen supply pipe connecting with the 80 oil chamber, and a vapor escape pipe, connecting with the second vapor chamber and having a valve for controlling the pressure and temperature of hydrogen and distilled oil vapor in contact with said contact material, substantially as described. 85

In testimony whereof I affix my signature in presence of two witnesses.
